DENTAL CUSPIDOR SHIELD

Harold H. Lavine, Washington, D. C.

Application June 22, 1948, Serial No. 34,445

3 Claims. (Cl. 4—263)

1

The present invention relates to a shield for a dental cuspidor.

One object of my invention is to provide a shield for a dental cuspidor which will prevent dental patients from expectorating beyond the walls of the cuspidor.

Another object is to provide such a device which may be easily attached and removed.

A further object of my invention is to provide such a device constructed of material which may be readily cleaned and sterilized.

A still further object of my invention is to provide such a structure which may be inexpensively manufactured and will be durable in use.

Other objects and advantages will become apparent upon considering the following specification when read in light of the attached drawings, in which

Fig. 1 is a front elevation of my invention attached to a standard dental cuspidor,

Fig. 2 is a top plan view of my invention attached to a dental cuspidor, and

Fig. 3 is a perspective view of the shield.

In the drawings wherein like numerals indicate like parts throughout the several views, the reference numeral 5 indicates generally the standard dental lavatory and cuspidor comprising a hollow standard 6 having at the top thereof a glass stand and drain 7, water supply pipe 8, arranged to feed water to a glass 9 standing on the glass stand and drain 7. An additional water supply pipe 10 leads from the standard 6. A cuspidor support 11 is attached to the standard 6 and contains a drain pipe therein. A cuspidor 12, having a funnel-shaped lower portion 13 for conveying fluid material from the cuspidor 12 to the drain in the cuspidor support 11, is mounted on top of the cuspidor support 11. The cuspidor 12 is further provided with an upstanding annular side wall 14, having an inturned lip portion 15 provided at its upper edge.

A shield 16 is formed from a semi-circular sheet of plastic stock and is provided with a multiplicity of flexible plastic hooks 17 on the outer lower face thereof. The hook members 17 are secured to the shield 16 by integral formation, gluing, screws, or any other suitable means. The lower corners 18 of the shield 16 are turned outwardly and upwardly to provide additional hook elements 19.

In the use and operation of the invention, the shield 16 is inserted within the interior of the cuspidor 12 with the lower edge of the shield 16 extending to the lower surface of the cuspidor

2

12. The hooks 17 are engaged over the outer edge of the annular wall 14 and the hooks 19 are engaged under the inner lower edge of the lip 15. This, as can be seen from Fig. 1, provides a rather stable locking arrangement to prevent accidental disengagement of the shield 16 from the cuspidor 12.

An opening 20 may be provided in one side of the shield 16 to permit the passage of the water supply pipe 10 through the shield 16 to the cuspidor 12.

In modern dental work, it is customary to paralyze the fifth trigeminal nerve and the seventh facial nerve with Novocain or other local anesthetic prior to performing any painful operation on the teeth. The paralysis of these nerves in turn paralyze or cause the loss of control of the facial muscles and the muscles of the tongue which interferes seriously with the patient's ability to control his expectoration, and consequently, a patient will oftentimes miss the dental cuspidor when he attempts to expectorate the blood and saliva collected in his mouth, following a dental operation, and will expectorate on the floor or wall. This, of course, creates both an unsanitary and an unsightly condition and presents a serious problem to the dentist in cleaning the premises after one patient has been released before the next patient can be admitted.

With my invention, the patient will be prevented from spreading expectorant over the premises and the shield may be easily and quickly cleaned by the dentist or his assistant before the next patient is admitted.

While I have disclosed one form of my invention, it is to be understood that various changes and modifications may be made without departing from the spirit or scope of this invention as defined by the appended claims.

I claim:

1. A shield for a dental cuspidor comprising a semi-circular body member, a pair of outwardly and upwardly extending hook elements formed on the two lower corners of the body member, a multiplicity of downwardly extending hook elements attached to the outer surface of said body whereby the body member is adapted to be inserted within a dental cuspidor with the first-named hooks engaged under the inturned lip of the cuspidor and the second-named hooks engaging over the outside wall of the dental cuspidor.

2. A device as claimed in claim 1 in which the body member and the hook members are formed of flexible plastic material.

3. A shield for a dental cuspidor of the type

comprising a bowl having a relatively flat bottom portion, downwardly converging into a drain portion, the outer circumferential edge of the bottom portion being flared upwardly and outwardly to form a side wall, and the top edge of said side wall being rolled inwardly and downwardly to form an in-turned lip comprising a semi-circular body member, a pair of outwardly and upwardly extending hook elements formed integrally with the body member by outwardly and upwardly bending the two lower corners, and a multiplicity of downwardly extending flexible hook elements attached to the outer surface of said body, said first-named hook elements being adapted to engage under the lip of the cuspidor in cooperation

with a pair of the second-named hook elements engaged over the outside wall of the cuspidor, the lip coacting with the first-named hook elements to prevent ready dislodgement of the shield from the cuspidor.

HAROLD H. LAVINE.
